No. 666,720.

Patented Jan. 29, 1901.

R. P. WETMORE.

COMBINED MATCH BOX AND TOOL HOLDER.

(Application filed Apr. 28, 1900.)

(No Model.)

UNITED STATES PATENT OFFICE.

ROBERT P. WETMORE, OF WASHINGTON, DISTRICT OF COLUMBIA, ASSIGNOR
OF ONE-HALF TO NORMAN M. VAUGHAN, OF SAME PLACE.

COMBINED MATCH-BOX AND TOOL-HOLDER.

SPECIFICATION forming part of Letters Patent No. 666,720, dated January 29, 1901.

Application filed April 28, 1900. Serial No. 14,692. (No model.)

To all whom it may concern:

Be it known that I, ROBERT P. WETMORE, a citizen of the United States, residing at Washington, in the District of Columbia, have invented certain new and useful Improvements in a Combined Match-Box and Tool-Holder; and I do hereby declare the following to be a full, clear, and exact description of the invention, such as will enable others skilled in the art to which it appertains to make and use the same.

This invention is a combined match-box and tool-holder.

It has for its object, among others, to provide a pocket match-box which shall serve, further, as a holder for a tool—such, for instance, as a corkscrew—which is so held within the box when not in use as to be prevented from being moved about or rattling and which may be easily removed from the box and inserted in a groove in the end of the box provided to receive and hold the same rigidly.

The invention is clearly illustrated in the accompanying drawings, which, with the letters of reference marked thereon, form a part of this specification, and in which—

Figure 1 is a perspective view of my improved pocket match-box closed. Fig. 2 is a plan view of the same with the lid thrown back and the corkscrew shown in operative position by dotted lines. Fig. 3 is a longitudinal section through the box on the line 3 3 of Fig. 2. Fig. 4 is a cross-section taken on the line 4 4 of said Fig. 2. Fig. 5 is a perspective view of the cutter and perforator removed, with the knob and spring left off. Fig. 6 is a perspective detail of one end of the box, showing the means for holding the implement, the latter being shown as about to be engaged therein. Fig. 6^a is a sectional detail.

Like letters of reference indicate like parts throughout the several views.

Referring now to the details of the drawings by letter, A designates the box proper, and B the lid. This lid is hinged in any suitable manner, as by hinges a, to the top edge of the rear side of the box, and a spring C is provided, which is secured at one end, as at b, to the inner face of the rear side of the box, and its free end is bent to form the lug

or flange c, which extends over the top edge of the rear side of the box, as seen best in Fig. 2, to be engaged by the under side of the lid as the latter is closed down. This spring 55 serves to throw open the lid when the latter is disengaged from the spring-catch at the front of the box. This spring-catch D may be of any of the well-known forms and is designed to be disengaged by pressure on the 60 push-button E in the usual manner.

At one end the box is formed or provided with a thickened portion F, having a longitudinally-disposed substantially T-shaped socket or groove G, adapted to receive the 65 correspondingly-shaped head H on the end of the shank I of a corkscrew or other implement, as seen best in Figs. 3 and 6, in the former of which the implement is shown in position with its head engaged in the socket 70 in dotted lines, while in Fig. 6 it is shown as just about to be entered therein. When not in use, the corkscrew or other implement is held firmly within the box, being there held by its head engaging beneath a lug K, secured to the inner wall of the end of the box, with entrance upon the under side, as seen clearly in Fig. 3. To insert the implement, it is turned in substantially a vertical position till the lug or flange upon one side of the 80 head is engaged in the socket formed by said lug, and then by pressing the implement down into its horizontal position the same will be firmly held against displacement, to be disengaged only by bringing it into its vertical position again. This lug is notched at its lower edge, so that the side walls of the notch will prevent sidewise movement of the head of the implement.

At the end of the box opposite the enlargement F there is an extension L, having the partition M, through an opening in which works the pin N, one end of which is pointed or sharpened, as seen in Figs. 2 and 5, while its other end is screw-threaded or otherwise 95 adapted to receive a knob or handle O, by which it may be manipulated, and between this knob or handle and the partition M is a spring P, which serves to normally keep the pin in its outermost position, but which is 100 compressed as the pin is pushed in, and when pressure is removed it returns the parts to

their normal position. This pin carries the cutter Q, which, as shown, is designed to reciprocate in the chamber of the extension, being guided by the side walls thereof, and its acting edges are sharpened, as seen best in Fig. 5. The top or bottom wall, or both, of the extension is provided with opening R for the introduction of the end of the cigar, which is then cut by pushing inward the push-pin, as will be readily understood. When it is desired to perforate the end of a cigar, the end is placed in the open end of the chamber of the extension and the pin pushed inward, entering the end of the cigar and perforating it in a manner well understood in the art.

It will be seen from the foregoing description that I have produced a simple and cheap, yet efficient and convenient, pocket match-box, cigar cutter and perforator, and handy implement-holder; but while the structural embodiment of the invention herein illustrated is what I at the present time consider prefer-

able it is evident that changes and variations may be resorted to without departing from the spirit of the invention or sacrificing any of its advantages, and I therefore do not wish to restrict myself to the precise details of construction herein illustrated.

What I claim as new is—

1. A match-box having at one end an enlargement with a socket to receive the head of the shank of an implement, and upon the interior of the box means to detachably hold the head of such implement, as set forth.

2. A pocket match-box having upon its interior wall a lug forming a socket between itself and the wall of the box with an entrance to said socket from the under side of the lug, as shown and described.

In testimony whereof I affix my signature in presence of two witnesses.

ROBERT P. WETMORE.
